UNITED STATES PATENT OFFICE.

ROBERT R. SINGER, OF PITTSBURG, PENNSYLVANIA.

MANUFACTURE OF METALLIC VEHICLE-TONGUES.

SPECIFICATION forming part of Letters Patent No. 469,952, dated March 1, 1892.

Application filed January 11, 1892. Serial No. 417,630. (No model.)

To all whom it may concern:

Be it known that I, ROBERT R. SINGER, of Pittsburgh, in the county of Allegheny and State of Pennsylvania, have invented a new and useful Improvement in the Manufacture of Vehicle-Shafts and other Hollow Articles, of which the following is a full, clear, and exact description, reference being had to the accompanying drawings, forming part of this specification, in which—

Figure 1 is an end elevation of my improved machine, the fly-wheel and main gearing being shown by dotted circular lines. Fig. 2 is a vertical cross-section of the machine on the line II II of Fig. 3. Fig. 3, Sheet 2, is a front elevation of the machine. Fig. 4 is an elevation of the moving die. Figs. 5 and 6 are end views of the opposite ends thereof. The figures on Sheet 3 are cross-sectional views on an enlarged scale, showing the dies. Fig. 7 shows the dies in the position which they occupy when the sheet-metal blank is first introduced between them. Fig. 8 shows them when the blank has been bent into trough form. Fig. 9 shows the dies as they are just before the closing in of the side dies. Fig. 10 shows the dies at the end of the shaping operation. Fig. 11, Sheet 4, is a plan view of the blank used in making a vehicle-tongue. Fig. 12, Sheet 4, is a view of the blank bent into final form, but before its edges have been united. Fig. 13 is a cross-section of dies of modified construction adapted to the manufacture of whiffle-trees or other hollow articles of curved cross-section. Fig. 14 is a similar view showing the dies in their final positions. Fig. 15 is a side elevation of the moving die; Fig. 16, a side elevation of the blank bent into final form by the dies of Figs. 13 and 14. Fig. 17 is an end view of a die of modified construction. Fig. 18, Sheet 2, is a plan view thereof. Fig. 19, Sheet 5, is a side elevation of a moving die and holder of modified construction. Figs. 20 and 21 are end views of opposite ends thereof. Fig. 22 is a plan view of said die. Fig. 23 is a plan view of the die proper detached from its holder. Fig. 24 is a plan view of the side dies used in conjunction with the dies of Figs. 19 to 23. Figs. 25 and 26 are opposite end views thereof. Figs. 27 to 30 are cross-sectional views, on a larger scale, of the dies of Figs. 19 and 24, showing them in the

positions which they occupy at the various stages of manufacture of the article.

The many disadvantages attending the use of the ordinary wooden vehicle-tongues, consisting in their liability to be injured by the weather and to be gnawed by the horses, and their weight make it very desirable to substitute for them metal tongues; but although there have been attempts made to this end, they have not been satisfactory, owing in part to the lack of efficient and economical machines for their manufacture. The object of my invention is to supply this want and to provide die mechanism by which metal tongues can be made rapidly and cheaply.

The tongues which I make by my improved machines are of sheet metal and are of tapering form, increasing in cross-section gradually from the tip to the butt, which is adapted to enter the hounds and at that part tapering in the opposite direction. The sheet metal is bent into this form and its meeting edges are secured by welding or riveting. This affords a strong and light article in every way desirable for use as a tongue. It is not liable to be broken or twisted, and if bent or dented can be readily straightened with ordinary blacksmith's tools. The machine which I employ for the manufacture of these tongues consist, essentially, in a mandrel, around which the tongue is bent and over which its edges are folded, in conjunction with suitable mechanism for so bending and forming the metal, said mandrel being divided longitudinally and the sections being tapered, so that they can be separated in order to permit the removal of the article from the mandrel, as hereinafter more fully described and claimed.

Referring to the drawings, in Fig. 12 I show in perspective view an unfinished vehicle-tongue made by means of my improved apparatus. The part 2 of the tongue, which is adapted to enter the hounds, tapers toward the butt, and the body 3 tapers in the opposite direction, and the whole is a hollow article bent in the desired shape and adapted to be secured at its meeting edges. In Figs. 4, 5, 6, 7, 8, 9, and 10 I show the die mechanism adapted to the manufacture of this tongue. It consists of a moving die or mandrel 4, which is shaped lengthwise to conform to the shape of the tongue to be produced, for this

purpose tapering in opposite directions, as above explained. That part of the mandrel which forms the rear portion of the tongue is divided longitudinally, so as to constitute 5 a separable section 5, which is secured to the part 4 by means of a keyway and tongue 6, as shown, the sectional division extending along the die to a point x , Fig. 3, at which the cross-sectional dimensions are a little less 10 than the dimension at the butt-end of the die. This mandrel or die is mounted in a machine, which may be of any suitable construction. I have illustrated in the drawings a convenient machine for that purpose, in which 15 7 15 represents a machine-frame having a die-head 8, adapted to move in vertical slides and connected by links 9 with eccentrics 10 on a shaft 11. The revolution of this shaft by the action of the eccentrics causes the die-head to 20 reciprocate vertically, and the moving die or mandrel 4 is secured to the die-head by suitable means. The female dies, in conjunction with which the moving die operates, are preferably constructed as shown in Figs. 1, 2, and 25 3, being constituted of two side wings or parts 12, which are set on slides in the frame of the machine and are adapted to be moved laterally by means of eccentrics 13, set on shafts 18 and provided with gearing operated 30 by means of the clutch 12', the clutch when moved in one direction being adapted to connect the shaft 11 with the power-shaft, and when moved in the other direction being adapted to connect the shafts 18 therewith. 35 The dies 12 are provided with lateral cavities 14, which are shaped to conform to the shape of the vehicle-tongue and are counterparts of the moving die 4. Between the two side dies is a bottom die-plate or base 16, which is preferably coextensive with the moving die. It is 40 movable vertically by cams 16' on the shaft 11, which cams bear against anti-friction rollers 25 on the base 16 and are provided with clutches 26, by which they may be connected 45 with or disconnected from the shaft. The respective cams and moving parts are so adjusted that in the operation of the dies in bending the sheet metal the blank B is clamped between the bottom of the die 4 and 50 the surface of the base 16, and that these parts shall move down simultaneously and at an equal rate between the female dies. The cams 16', by which the base is operated, are made concentric at portions b of their peripheries, so that when the base 16 is being elevated by the cams its upward motion shall 55 stop before the die-head 8 has reached the limit of its upstroke, thereby causing a momentary separation of the die and base and 60 enabling the interposition of the metal blank B.

In using the machine when the side dies 12 are separated and the moving die elevated above them, a sheet-metal blank B, from 65 which the tongue is to be made, is laid upon the top of the separated dies 12 between the

moving die and the base 16, Fig. 7. The moving die and base are caused to clamp the blank between them, and are then caused to descend, thereby forcing the blank down between the upper portions 15 of the side dies and turning up the sides of the blank against the moving die, as shown in Fig. 8. During this motion the blank, being clamped between the lower surface of the moving-die and the base, is prevented from danger of distortion or bending. When the blank has thus been bent into trough shape, the side dies are separated somewhat and the moving die forced down into the position shown in Fig. 9. Then 80 the cams of the base-piece 16 are disconnected from their power-shaft and the moving die is raised to its original position, leaving the tongue-blank between the side dies. The section 5 of the moving die or mandrel is then 85 removed by pulling it lengthwise from the body portion and the die is caused to descend into its position between the side dies. The side dies are then caused to approach, and the upper parts 15 thereof, engaging the projecting portions of the blank, bend them inwardly over the upper portion of the moving die, completing the formation of the tongue and shaping vertically-projecting flanges or lips on the adjacent edges of the metal, Fig. 95 10, while the hollow tongue-body is shaped between the cavities 14. The side dies are then separated and the moving die is raised above them, lifting with it the metal blank, and the blank is then pulled lengthwise from 100 the smaller end of the moving die, the end of the machine-frame being provided for this purpose with a gap or cavity opposite to the die. The edges of the blank being then unattached to each other will yield laterally 105 sufficiently to permit this removal, because of the fact that the lower portion of the thicker end of the die has been removed, the upper portion only opposite to the more-yielding upper edges of the blank being present. 110 When the blank has been removed, its edges are secured either by welding or riveting, thus forming a closed hollow article of great strength and rigidity.

Many modifications in the form and construction of my machine may be made within the scope of my invention. Thus the machine itself and the mechanism for actuating the various parts may be altered and other means for transmitting power—such as motor-cylinders and plungers—may be substituted for the cams. Instead, also, of making the moving die or mandrel of two separable sections, it may be made of three or more of such sections, or where the dies are to be employed in making tongues tapering in one direction only the moving die may be made of a single piece. These constructions I intend to cover in the broad claims of the application.

The dies shown in Figs. 13 and 14 are adapted to be used in the manufacture of articles—such as whiffletrees, vehicle-tongues, &c.—

having curved cross-section. Here the two side dies are adapted to be closed when the blank is first bent into trough form and are provided at the top with a cavity *b* of trough shape conforming to that of the moving die. The moving die is constructed as above described, except that it is of curved outline in cross-section. In using these dies the blank is first placed on the surface of the closed side dies, the moving die is caused to descend and to bend the blank into trough form in the surface cavity *b*, (see Fig. 13,) the side dies are then opened, the lower section of the moving die is withdrawn and the remainder is caused to descend, so as to bring the blank into the cavity 14, and the side dies are then closed upon the blank to give to it a final shaping around the moving die. (See Fig. 14.)

In the figures on Sheet 5 I show dies which are adapted not only to shape the blank, but to lap the edges together, thus bringing them into proper position for welding or riveting. The moving die shown in these figures is not sectional, but is made of a single piece, being adapted to the manufacture of articles tapering only in one direction. By making the moving die in sections, as hereinafter described and as illustrated in Fig. 17, these dies can be used for making tongues which taper in opposite directions.

The moving die 4' (shown on Sheet 5) is provided on its surface with a series of key-holes or slots *c*, adapted to be engaged detachably by a series of keys 20, which pass through the plunger or die-holder 21 and are connected by arms 22 and a connecting-rod 23, so as to be capable of simultaneous operation. Other attaching devices may be substituted for these keys. This moving die is of the shape and size desired to be given to the finished article. The side dies 12' are substantially the same in construction as the corresponding parts shown in Fig. 7, except that they are adapted to close together, as shown in Fig. 29. The base or die 16' corresponds to the part 16 of Fig. 7. In using these dies the blank B is placed and clamped between the moving die and base, as in Fig. 27. These parts are caused to descend between the side dies and to bend the blank into trough form. The die-holder is then detached by loosening its keys and is withdrawn from the moving die, as shown in Fig. 28. The side dies are then closed, as shown in Fig. 29, so as to shape the blank around the moving die and to fold the edges of the blank together, and, finally, the side dies are opened, the base 16' elevated to lift the blank, and the blank then removed longitudinally from the inclosed die.

In Fig. 17 I show a modification of the moving die above described adapted to the manufacture of tongues tapering oppositely in both directions. For this purpose the die is made of three co-extensive sections *g i h*, the middle section *i* being of wedge form. When the blank has been removed from the

side dies, as shown in Fig. 30, the middle wedge-section is withdrawn, thus causing the other two sections to be drawn together laterally and reducing their conjoined cross-section, so that they can be removed with ease.

It will be understood that in addition to its use for the manufacture of vehicle-tongues the combination of dies which I have devised may be employed for making whiffletrees, singletrees, neck-yokes, or similar tubular sheet-metal articles.

I claim as my invention—

1. In apparatus for making tubular metal articles, the combination of a vertically-movable shaping-die, side dies between which the shaping-die is adapted to move, and means for moving the shaping-die vertically and for moving the side dies laterally after the metal has been bent into trough form by the shaping-die, substantially as and for the purposes described.

2. In apparatus for making tubular metal articles, the combination of a vertically-movable shaping-die, side dies between which the shaping-die is adapted to move, means for moving the shaping-die vertically and for moving the side dies laterally after the metal has been bent into trough form by the shaping-die, a base-piece adapted to move with the shaping-die and to act in conjunction therewith to clamp an interposed metal blank and shape its bottom, and means for moving the base-piece, substantially as and for the purposes described.

3. In apparatus for making tubular metal articles, the combination of a vertically-movable shaping-die, side dies between which the shaping-die is adapted to move, and means for moving the shaping-die vertically and for moving the side dies laterally after the metal has been bent into trough form by the shaping-die, said side dies having portions 15, between which the metal is bent into trough form by motion of the shaping-die and having cavities 14, substantially as and for the purposes described.

4. In apparatus for shaping hollow tapering metal articles, a moving die shaped to conform to the article to be produced and divided longitudinally into separable sections, substantially as and for the purposes described.

5. In apparatus for shaping hollow tapering metal articles, a moving die shaped to conform to the article to be produced and divided longitudinally into separable sections, of which the lower section is removable, in combination with female dies, substantially as and for the purposes described.

6. In apparatus for shaping hollow metal articles which taper longitudinally in both directions, a moving die shaped to conform to the article to be produced and having its thicker end portion divided longitudinally in separable sections, substantially as and for the purposes described.

7. In apparatus for making tubular metal articles, the combination of a vertically-movable shaping-die, a female die with which it operates to bend the metal, and means for forcing the bent edges of the metal over the shaping-die, substantially as and for the purposes described.

In testimony whereof I have hereunto set my hand this 2d day of January, A. D. 1892.

ROBT. R. SINGER.
